UNITED STATES PATENT OFFICE.

PERRY BROWN, OF LOUISVILLE, KENTUCKY.

CAR-COUPING.

SPECIFICATION forming part of Letters Patent No. 366,712, dated July 19, 1887.

Application filed October 23, 1886. Serial No. 217,049. (No model.)

To all whom it may concern:

Be it known that I, PERRY BROWN, a citizen of the United States, residing at Louisville, in the county of Jefferson and State of Kentucky, have invented certain new and useful Improvements in Car-Couplings, of which the following is a specification, reference being had therein to the accompanying drawings, in which—

10 Figure 1 is a side elevation of two cars coupled together and provided with my improvement. Fig. 2 is a bottom plan of the same with a buffer substituted for one of the dead-woods, and Fig. 3 is a sectional detail.

15 This invention relates to car-couplings of that class in which the cars are automatically coupled as they come together; and the invention consists in the peculiar combinations and the novel construction and arrangement of 20 parts, as more fully hereinafter described, and then particularly pointed out in the claims.

Referring by letter to the accompanying drawings, which illustrate the preferable form of my improvement, A represents a portion of 25 a car, which car is supported upon wheels (not shown) in the ordinary manner.

B is a "dead-wood" secured to the end of the car, and is formed with a transverse opening to receive the coupling link, and with a 30 horizontal recess to receive and allow of the vertical play of the coupling hook or lever C, which is pivoted on the transverse shaft D, supported in suitable bearings on the bottom of the car. The lever C is formed with a hook, 35 c, designed to drop into an opening, b, in the bottom of the dead-wood, as shown in Fig. 3. This lever is also provided with an arm, C', projecting rearward of its pivotal point, for a purpose hereinafter explained.

40 A' are the brace-rods, secured to the under side of the car and provided with ears or lugs d', which form bearings for the transverse shaft E.

F is a link connecting and bracing the shafts 45 E D.

G is a hooked lever, fulcrumed on the shaft D and provided with a tail-extension, G'. At the opposite side of the shaft D is the eye H, formed, preferably, in the bar H', sleeved on 50 the shafts D E. The shaft D is supported in suitable bearings, secured to the under side of the car in any well-known way.

I is a releasing-lever, fulcrumed on the shaft D in proximity to the eye H, and provided with an offset or bend, so as to bring its 55 head i in vertical line with the opening in the eye H, as shown in Fig. 2. The shafts D E are provided with nuts at one or both ends, in order that the parts sleeved thereon may be readily removed when necessary. 60

Intermediate of the two shafts D E is journaled in suitable bearings beneath the car the transverse shaft J, to which are secured the dogs J' J'' J'', arranged in such relative positions as to engage the tails of the levers C, G, 65 and I, respectively, as shown in Fig. 2.

The levers C and G will ordinarily return to their normal position, which is that shown by full lines in Fig. 1, by gravity; but to aid them in their return to such position I sometimes employ a spring, as K, coiled around the shaft D, with its ends extending in opposite directions and bearing upon the under side of the tails of the lever C G, as shown in Fig. 2. The ends of the shaft J are bent at 75 right angles to its length to form handles j, by which it is operated.

L are plates pivoted to the under side of the car, and between these plates and the bottom of the car the shaft J passes. 80

The dead-wood B, coupling-lever C, and dog J' may sometimes be omitted, as the levers G and eyes H, with their accessories, form the main means of coupling; and when these parts are omitted I generally substitute therefor a 85 spring buffer, as shown at the left of Fig. 2, which buffer is constructed as follows:

M is a casting or block secured to the end of the car and formed with a tapering socket, m.

N is a rod carrying the buffer-head N', which 90 is tapering to correspond inversely with the socket m.

O is a cylinder supported in any suitable way beneath the car, and through which the rod N passes, the inner end of said rod being 95 supported either by the block o or by a suitable support on the shaft E, and is provided with an adjusting-nut, n. Around this rod, within the cylinder, is a coiled spring, P, finding one point of resistance against the end of the cylinder and the other against a shoulder (not shown) formed on the rod N within said cylinder. In use the buffer-head receives the force of the shock occasioned by the coming

together of the cars, which is taken up by the spring. In case of extra strong shocks, such as occasioned by two cars coming together with an extraordinary great speed or force, the 5 buffer-head will be forced into the socket, and the two opposite blocks, coming in contact, relieves the spring of the strain and prevents injury thereto or to the buffer-head.

In operation, supposing it is desired to 10 couple two cars together provided with my couplings, the shaft J on each car is turned so as to allow the front ends of the levers G and I to fall to their normal position; and as the cars approach each other the lever G comes in 15 contact with the eye H, the inclined portion of the hooked end of the said lever readily allowing the same to ride up and fall into said eye. When it is desired to hold the parts in such a position that they will not couple, the 20 shaft J is turned so as to depress the rear ends of the levers C, G, and I, which will of course elevate the forward ends of the same, and the plate or plates L turned at right angles to their normal position, as shown in dotted lines in 25 Fig. 2, when the said shaft cannot be revolved, and the levers are kept in their elevated position. When it is desired to uncouple, it is only necessary to turn the shaft J, when the 30 dogs thereon will elevate the hooked levers and the releasing-lever, so as to disengage the parts, as will be readily understood.

If a car having only an ordinary link-coupling is to be connected with a car provided with one of these couplings, the link of said 35 ordinary coupling is run into the dead-wood B, and as its ends strike the inclined portion of the nose of the lever C the latter rises, and the link continuing to advance, the nose of the hook falls into the link, and the car is thus 40 surely coupled; or the two means of coupling may be jointly used, so that in case of one breaking, as sometimes occurs, the other coupling still remains good. I, however, propose usually to dispense with the dead-wood B and 45 its lever, except when there is a possibility of the car being used in connection with a car having an ordinary coupling.

It will be readily seen that by this construction a very convenient coupling is made, that 50 is not only automatically coupled or uncoupled when required without danger, but one that can be automatically coupled with cars having the ordinary coupling, and, moreover, the strain is transverse from the car frame to the truss- 55 rods.

What I claim as new is—

1. The combination, with a car and truss-rods, of a transverse shaft journaled on said rods and one part of a coupling sleeved on 60 said shaft, substantially as described.
2. The combination, with the car and the truss-rods A', secured thereto and having formed integral therewith the ears a', of the transverse shaft E, having bearings in said

ears, and one part of a coupling sleeved on 65 said shaft, substantially as described.

3. A two-part coupling, one part consisting of a pivoted hook and the other of a bar, as H', having formed integral therewith the eye H to receive the hook of the opposite 70 coupling, and both independent of the buffer, substantially as described.

4. The combination, with a two-part coupling, each part having a hook adapted to catch on the opposite part of the coupling, of a dead-wood set centrally between the hooks and 75 provided with a coupling-hook adapted to automatically engage with a link from an ordinary coupling, substantially as described.

5. The combination, with a coupling having 80 a hook and eye, of the lever I, independent of the coupling and having a hook adapted to lift the nose of the hook out of the eye, and a shaft independent of the said lever for operating the same, substantially as described. 85

6. The combination, with a two-part coupling having a hook and eye on each part, of a central buffer provided with a coupling-hook and a shaft having dogs, as J' J² J³, for simultaneously lifting the hooks on each part, 90 and the hook of the buffer, substantially as described.

7. The combination, with a two-part coupling having a hook and eye on each part, of a central stationary dead-wood having a spring-buffer therein, substantially as described. 95

8. The combination, with a two-part coupling having a hook and eye on each part, of a central spring-buffer provided with a stationary dead-wood, having a socket adapted 100 to receive the head of the buffer and the entire strain of the shock when under extraordinary pressure, substantially as described.

9. The combination, with the levers G and I, of the shaft J, provided with dogs J² J³, and the pivoted plate L, constructed to engage said shaft, substantially as and for the purpose specified.

10. The combination, with the transverse shaft E and the bar H', sleeved thereon at one 110 end and formed with the eye H at the other, of the rock-shaft J and the lever I thereon, and having offset to bring its head i in vertical line with said eye, substantially as described. 115

11. The combination, with the block M, having tapering socket, of the rod N and the buffer-head N', carried by said rod, and tapered, and the spring P around said rod outside of 120 said socket, substantially as and for the purpose specified.

In testimony whereof I affix my signature, in presence of two witnesses, this 15th day of October, 1886.

PERRY BROWN.
